UNITED STATES PATENT OFFICE.

JOHN HARRIS, OF LAKEWOOD, OHIO, ASSIGNEE OF ONE-HALF TO JAMES R. ROSE.

ELECTROLYTIC CELL.

1,297,157.

Specification of Letters Patent. Patented Mar. 11, 1919.

Application filed September 29, 1917. Serial No. 193,873.

To all whom it may concern:

Be it known that I, JOHN HARRIS, a citizen of the United States, residing at Lakewood, in the county of Cuyahoga and State 5 of Ohio, have invented a certain new and useful Improvement in Electrolytic Cells, of which the following is a full, clear, and exact description, reference being had to the accompanying drawings.

10 This invention relates to apparatus for the generation of hydrogen and oxygen by electrolysis of water and has for its general object to so construct and arrange the parts of such apparatus as to prevent a mixing of the 15 hydrogen and the oxygen; also to provide an apparatus of this character having a greater capacity and output for the same dimensions of cell than those heretofore employed. Further and more limited objects of the invention 20 will be realized in and through the construction and arrangement of parts described in the specification and embodied in the claims appended hereto.

In the drawings Figure 1 represents a longitudinal sectional view through an electrolytic cell constructed in accordance with my invention, certain of the units thereof being shown in section and certain others in elevation. Fig. 2 is a sectional detail corresponding to the line 2—2 of Fig. 1, certain parts being broken away; Fig. 3 a perspective view of one of the clamping rings employed in the construction of one of such units, and Fig. 4 a detail in section of one of the electrodes and the parts adjacent thereto.

Describing the various parts illustrated herein, 1 denotes a tank having therein the electrolyte 2, said electrolyte being preferably a 10% solution of sodium hydroxid in 40 water. 3 denotes supports located on opposite sides of the bottom of the tank and extending preferably the full length thereof, each support being formed of insulating material and having its inner face rabbeted to 45 provide a seat, as indicated at 3^a for the lower ends of the units, which will now be described.

Each unit comprises a narrow open bottom casing 4 of sheet iron, fiber, or other suitable material having in each side wall thereof an aperture surrounded by an outwardly projecting flange 5. The apertures are shown as oval or elliptical, but may be of any suitable shape. Within each flange, there is 55 mounted an electrode 6, said electrode being preferably of cast iron having the outer face

thereof provided with projections 6^a. These projections are rounded or knob-like and are shown as arranged in vertical rows with the projections of one row staggered horizontally and vertically with respect to the projections on the adjacent row or rows. Each electrode is of the same shape as the flange 5 but is sufficiently smaller than said flange to enable it to be inserted therewithin and to 65 provide a space between the periphery of the electrode and the inner wall of the flange. For the purpose of providing a uniform space between the flange and the electrode, the latter may be provided with spacing lugs 70 of non-conducting material indicated at 6^b. 7 denotes a diaphragm (preferably of asbestos) which is applied to the opposed flanges 5 adjacent units by means of a common clamping ring 8. The clamping rings 75 will be of such width as to abut against the sides of opposed cell units and space apart and thus provide a chamber between opposed adjacent diaphragms. This chamber is defined by the clamping ring and the dia- 80 phragms and the ring is perforated in its upper portion, as indicated at 8^a. The units will be supported in proper position within the tank and the parts will be held in operative relation to each other by means of a 85 screw threaded through an insulating bushing 10 in one of the end walls of said tank, said screw bearing against a plate 11 which in turn is adapted to press against the side of the unit adjacent thereto. The end units 90 of the cells will each preferably be provided with a cap 12 which is slipped over the flange 5. By operating the said screw the units may be removed or inserted as desired and may be held in proper relation to each 95 other when assembled within the tank.

Each unit 4 is provided with a neck 4^a having therein a removable stopper or closure 4^b of insulating material and through which the wire 13 is led to a transverse bar 100 14 (preferably of cast iron) extending between the electrodes 6. Each alternate unit will receive a conductor leading from the positive side of the source of electrical energy, the other units receiving therewithin 105 a conductor leading from the negative side of such source of energy. Each unit is also provided with an outlet connection 4^c from which a tube (not shown) leads to a suitable storage compartment (not shown).

In operation, current being supplied to the various units, oxygen will be generated with-

in each of one set of units and hydrogen within each of the other set of units. The oxygen and hydrogen will be liberated from the outer surfaces of opposed electrodes, 5 there being no gas liberated from the electrodes facing the end walls of the tank, and will pass inwardly around the edges of such electrodes, into the upper portions of the corresponding units, whence the gases will 10 be delivered through the connections ^{4e} to the appropriate receptacles.

The manner of supporting the units permits the electrolyte to circulate freely therein. Normally there will be no passage of 15 gases through the diaphragms 7. However, should the pressure in one of the receiving tanks be sufficient to displace the electrolyte in either set of units below the top of the electrodes thereof, the gas may be forced 20 through the diaphragms which cover such electrodes. In this case, the gas will not pass through the diaphragms covering the electrodes of adjacent units, as a path of less resistance is provided therefor through the 25 spaces or chambers provided between the pairs of diaphragms and through the apertures in the clamping rings 8. Hence, in the operation of my cell, there is no danger of mixing the gases.

30 Furthermore, by providing each unit with a pair of electrodes, the capacity of the cell is practically double that of any other cell of like dimensions. The arrangement of the electrodes with reference to each other and 35 with reference to the bars 14 permits me to employ the screws 9 and plates 11 as a convenient means for assembling and disassembling the units.

Having thus described my invention, what 40 I claim is:—

1. In an electrolytic cell, the combination of a tank, a plurality of cell units within said tank, each of said units having openings in opposed walls thereof, electrodes 45 within said openings, a bar of conducting material interposed between the electrodes in each unit, and means mounted in one of the walls of the tank and co-operating with the side of the unit adjacent thereto for exerting pressure upon such electrodes thereby to hold said units in assembled position.

2. In an electrolytic cell, the combination of a tank having opposed walls, a plurality of cell units within said tank and extending 55 substantially parallel with said walls, each of said units having flanged openings in opposed sides thereof, the flanges projecting toward said walls, electrodes within said openings, diaphragms covering the opposed 60 flanges of such units, clamping rings securing said diaphragms to such flanges, a bar of conducting material interposed between the electrodes in each unit, a cover for the flange of each end unit which faces the tank 65 wall adjacent thereto, and means mounted

in one of such tank walls and co-operating with the cover adjacent thereto for applying transversely of such units thereby to hold said units in assembled position.

3. In an electrolytic cell, the combination 70 of a pair of units each comprising a casing and having each an opening in one side facing the corresponding opening in the side of the other casing, an electrode within each of said openings and spaced from the side 75 corresponding thereto, a diaphragm covering each of said openings and the electrode therewithin, and means for assembling said units side by side and for providing a space between said diaphragms, said space being 80 provided with an outlet for the escape of gas.

4. In an electrolytic cell, the combination 85 of a pair of units each comprising a casing having an opening in the side wall thereof and a flange surrounding said opening, the flanges being presented toward each other, an electrode within and peripherally spaced from each flange, a diaphragm extending across each opening, and a clamping ring 90 adapted to receive therewithin the said flanges and the peripheral portions of said diaphragms, said clamping ring having one or more openings in the upper portion thereof.

95 5. In an electrolytic cell, the combination of a pair of units each comprising a casing having an opening in the side wall thereof and a flange surrounding said opening, the flanges being presented toward each other, 100 an electrode within and peripherally spaced from each flange, a diaphragm extending across each opening, and a clamping ring adapted to receive therewithin the said flanges and the peripheral portions of said 105 diaphragms, said clamping ring having one or more openings therein, the said flanges and diaphragms being spaced apart thereby to provide a chamber communicating with the opening or openings in the clamp- 110 ing ring.

6. As a new article of manufacture, an electrolytic cell unit having an opening in the side wall thereof and an outwardly projecting flange extending about said opening, 115 an electrode within said opening and spaced from the side of such unit, a diaphragm extending across said opening, and a clamping ring securing the peripheral portion of said diaphragm to said flange.

120 7. As an article of manufacture, an electrolytic cell unit comprising a casing having openings in opposed walls thereof, an electrode within each opening and spaced from the wall corresponding thereto, a dia- 125 phragm of permeable material covering each of said electrodes, and means for securing said diaphragms in place.

8. As a new article of manufacture, a cell unit comprising a casing having openings 130

- in opposed walls thereof, each of said openings being surrounded by an outwardly projecting flange, an electrode within each of said openings and spaced from the wall 5 corresponding thereto, a diaphragm of permeable material applied to each flange, and a clamping ring securing the peripheral portion of said diaphragm to the corresponding flange.
10. 9. As a new article of manufacture, a cell unit comprising a casing having an upper gas collecting chamber and provided with opposed openings below said chamber, an electrode within each opening and having 15 its periphery spaced from the wall thereof to provide a passageway for gas from the outside of each electrode inwardly around the edge thereof to said chamber, and a bar of conducting material interposed between said electrodes and engaging the inner faces 20 thereof.
10. As a new article of manufacture, a cell comprising a casing having an upper gas-collecting chamber and provided with an opening in the wall thereof below such 25 chamber, an electrode in said opening and peripherally spaced from the wall thereof to provide a passageway for gas from the outside of the electrode inwardly through the peripheral space to said chamber, and 30 means for supplying electric current to said electrode.

In testimony whereof, I hereunto affix my signature.

JOHN HARRIS.
